UNITED STATES PATENT OFFICE.

CHARLES OWENS, OF CHATTANOOGA, TENNESSEE.

ADDRESSING-MACHINE.

No. 826,058.

Specification of Letters Patent.

Patented July 17, 1906.

Application filed April 23, 1904. Renewed July 25, 1905. Serial No. 271,264.

To all whom it may concern:

Be it known that I, CHARLES OWENS, a citizen of the United States, residing at Chattanooga, Tennessee, have invented certain new and useful Improvements in Addressing-Machines, of which the following is a specification.

My invention relates to addressing-machines of the class in which stencils are employed in connection with inking mechanism for applying the name address to the magazine, paper, or other article.

One of the objects of my invention is to provide a machine in which the operation of the stencil-feeding means and the impression or printing means will depend upon the presence of the magazine or paper to be addressed, so that when a magazine is present to have the address printed thereon, the said parts of the machine will be set in motion, while on the other hand, if no magazine or paper is fed to or toward the printing-point there will be no operation of the stencil-feeding mechanism and the impression or printing means.

Another object of my invention is to provide means for throwing out of operation the machine or mechanism which feeds the magazines to the point where they are addressed when the supply of stencils becomes exhausted from the hopper or stencil-holder, as a result of which the stencil-feeding means and printing means will remain inoperative so long as no stencils are in the hopper.

The invention consists in the features and combination and arrangement of parts hereinafter described, and particularly pointed out in the claims.

In the accompanying drawings, Figure 1 is a side view of the invention, some of the parts at the front of said figure being omitted; but indicated in dotted lines, and some of the hidden parts being also shown in dotted lines. Fig. 2 is a plan view. Fig. 3 is a front elevation looking from the left of Fig. 1; Fig. 4, a detail view of the cam-ring and switch-lever. Fig. 5 is a view of the opposite side of the cam-ring and switch-lever from that shown in Fig. 4. Fig. 5^a is a detail perspective view of the switch-lever. Fig. 6 is a detail sectional view. Fig. 7 is a diagrammatic view of the machine and its connections to the feeder for the magazine or other article.

In carrying out my present invention I utilize some of the features disclosed in Letters Patent of the United States granted to me

August 4, 1903, No. 735,405, and particularly as regards a step-by-step-moving carrier having pawls to engage a constantly-rotating part, the movement of said carrier being controlled by the presence of a magazine or paper fed to the machine.

In the present instance the carrier is used to convey the stencils one by one to the printing-point, and the step-by-step movement of the carrier, as well as the operation of the printing mechanism, depends upon whether or not a magazine or paper is fed to the machine to be addressed.

In the drawings, 1 indicates a hopper or holder for the stencils. 2 represents an impression-roller or rotary platen; 3, an inking pad or roller, while 4 indicates traveling bands or strips running parallel and adapted to convey the magazines or papers to the said platen and roller for receiving the impression, for which purpose the stencils are also conveyed to a point beneath the magazines or papers and between the same and the inking pad or roller.

The stencils are fed to the printing-point by a carrier or feeder composed of a rotary frame. This is made up of a side or wheel 5, arranged to turn freely on a shaft 6 and having connected thereto a circular rim 7, which is of the same diameter as the wheel or disk 5. This circular rim is supported from the wheel or side 5 by the brackets or bars 9, extending from the inner lateral face of the said wheel and joined to the inner face of the rim, screws 10 being used as the means of connection. This construction provides a rotary frame made up of a side or wheel supported freely on the shaft 6 and carrying an overhanging circular rim of the same diameter and spaced apart therefrom by means of the supports or brackets. This frame or feeder carries teeth 11, projecting from the inner side of the wheel beyond the periphery of the same and adapted to engage the lowermost stencil of the pile in the magazine or hopper 1 and feed or carry the same therefrom to the printing-point. In order to assist in carrying the stencils, I provide bosses 12 on the outer sides of the rotary carrier or frame, said bosses being rubber-covered and arranged at points opposite the teeth to coact therewith in feeding the stencils by their rubber-covered surfaces engaging the lower face of the stencils. The normal position of the carrier when at rest in relation to the

stencil holder or hopper is indicated in Fig. 1 with the teeth 11 disposed on opposite sides of the hopper and at some distance therefrom. From this position the carrier is 5 started, and the teeth engage with the stencils after they (the teeth) have been set in motion, and said teeth carry the stencils around to a point adjacent the latch, and the machine then comes to rest. During this 10 time the stencil of course has been resting on the periphery of the rims of wheels.

It will be noticed that the traveling bands for carrying the magazine, paper, or other article extend substantially tangential in relation to the periphery of the feeder or carrier for the stencils, and the magazine or other article is thus directed into proximity to the carrier.

The magazine, like that disclosed in my 20 patent above mentioned, controls the step-by-step movement of the carrier, and in the present case this is accomplished as follows: On the shaft 6 a ratchet-wheel 13 is fixed to rotate constantly therewith. The side 5 of 25 the carrier-wheel has pivoted thereto at 14 a series of pawls 15, the teeth of which are adapted to engage the teeth of the ratchet-wheel when said pawls are allowed to drop into engagement therewith. The pawls and 30 the manner in which they are controlled are similar to what is disclosed in the patent referred to. Each pawl carries near its front end a laterally-extending pin 16, which enters a lateral groove 17 in a ring 18, which is 35 rigidly secured to the frame of the machine in any suitable manner. These pins engaging the groove hold the pawls out of contact with the teeth of the ratchet-wheel. The ring 18 is cut away at 19, so that the pawls 40 drop into engagement with the teeth of the ratchet-wheel, and for controlling this action I employ a switch-lever pivoted at 23 to the stationary ring on the outer face thereof, the said switch-lever being indicated at 20 and 45 having at its free end laterally-extending flanges 21, forming continuations of the flanges or walls of the guide-groove 17 of the stationary ring or frame. This switch-lever is held up, so that the space 21* between the 50 flanges 21 will form a continuation of the groove 17, by a latch 22, pivoted at 23* on the outer side of the stationary ring or frame, the said latch having a shoulder 24 to engage a projection 25 on the switch-lever. The 55 latch is drawn toward the projection by a spring 26. Another spring 27 draws the switch-lever downwardly when it is released from the latch. The latch extends upwardly into the path of the magazine, paper, 60 or other article which is being carried along by the traveling bands.

As above stated, the carrier is normally at rest, and its uppermost pair of teeth are holding a stencil adjacent the bands 4 and immediately below the same. The bands are di-

rected by guide-rollers 28 on shafts 29, and a magazine or paper moving with the bands will strike the upper end of the latch and operate it to release the switch-lever, thus allowing the pawl being held up by the switch-lever to drop down into engagement with the ratchet-wheel. The carrier will now begin to rotate with ratchet-wheel, and the pin 16 on the pawl will ride on an inclined edge 30, which, it will be seen, will lift the pawl out of engagement with the ratchet-wheel as the pawl approaches the end 31 of the incline, and at the moment this disengaging action takes place the pin 16 on the next following pawl will engage a stop 31', which is arranged directly opposite the mouth of the switch-lever, which has now been raised to its normal position, as will be hereinafter described.

From what has just been stated it will be seen that the carrier is given a step-by-step movement by means of the magazines acting in succession upon the latch 22, thus releasing the pawls successively from the switch-lever and from the stop 31', each pawl as it falls engaging the ratchet-wheel, and thus 95 causing the carrier to be moved until the pin on the pawl has moved up the incline 30 and the pawl has been withdrawn from the ratchet-teeth, the next pawl having been brought around by this movement of the carrier so 100 that its pin 16 will be resting in the switch-lever and against the stop 31', by which the movement of the carrier is arrested. The switch-lever is raised to normal position 105 against the action of its spring by pins 32 on the carrier, projecting laterally therefrom and arranged to engage an overhanging flange 33 on the switch-lever, so that the switch-lever is raised and the latch engages and holds the same just before the pin 16 on the pawl arrives at the flange 21 of the switch-lever.

It will be understood that the step-by-step action just mentioned will take place provided the feed of the magazines is such as to allow the switch-lever to rise and the next 110 pawl, above mentioned, to be directed thereby, so as to be arrested by the stop 31' before the next magazine has struck the latch 22; but, on the other hand, if the feed of the magazines is such that the latch 22 is operated 115 just before the next pawl arrives thereat it will be clear that said next pawl will be directed by the switch so that instead of striking the stop 31' it will engage with the teeth of the ratchet-wheel, and thus the carrier will 120 be kept in continuous rotation so long as the magazines arrive in proper order or time. It is also important in this construction to note that in my invention the carrier is normally at rest and is started by a magazine being fed thereto, after which its movement will be either continuous if the magazines are fed thereto in succession or step-by-step if the magazines are fed thereto irregularly or 125 out of proper time.

It will be noticed that because the carrier is holding a stencil adjacent the point at which the carrier and the bands 4 converge and also because of the fact that the latch is located at this point the stencil will register with the oncoming magazine, and as the carrier immediately begins to move when the magazine operates the latch the stencil and the magazine will move forward together to 10 the printing mechanism and with the stencil below the magazine. A shield is provided at 34, under which the stencil moves, one of these shields being arranged opposite the periphery of each side of the carrier and 15 curved to conform thereto.

The printing mechanism comprises the stencil and impression roller or platen 2, carried by a shaft 36 and arranged over the path of the magazine. On the under side of the 20 path of the magazine an inking pad or roller 3 is arranged on the shaft 38. This shaft extends in from the right-hand side of the rotary frame or carrier and beneath the overhanging rim 7, and it carries the inking pad 25 or roller upon its inner end. This inking-pad receives its supply of ink from an inking-roller 39, partly immersed in ink within a fountain 40. This inking-roller is on a shaft 41, extending out toward the right of the 30 machine.

The inking mechanism is driven by gearing consisting of a gear-wheel 42 on a sleeve 43, connected with the wheel or side 5 of the carrier, which sleeve rotates on the main shaft 6. 35 This gear meshes with a gear 44 on the shaft of the impression roll or platen, and this shaft is geared to the shaft of the inking-roller by the gears 45 and 46. The inking-roller is driven through the gear 46 just mentioned 40 and the gear 46^x.

It will be seen from the above that the carrier for feeding the stencils depends for its feeding action upon the presence of a magazine or other article to receive the address. 45 If such article is fed forward by the carrier-bands, a stencil will be fed forward to print the address thereon; but no stencil will be fed forward when there is no article to be addressed.

50 I also provide means whereby the machine will be controlled by the presence or absence of the stencils in the hopper, and for this purpose I provide a follower in the hopper adapted to rest on the pile of stencils and having 55 on its lower face a contact-point 48, to which a conducting-wire 49 extends. A second point 50 is arranged at the bottom of the hopper, adapted to be struck by the contact first mentioned when the hopper of stencils 60 has become exhausted and the follower reaches the bottom thereof. This will close an electric circuit and operate a suitable clutch-controlling mechanism which feeds the magazines or delivers to the bands. In 65 this way the stencil-feeding frame will be con-

trolled by the presence or absence of the stencils in the hopper, as well as by the presence of a magazine in the bands.

It will be observed that I have associated a step-by-step carrier for the stencils with a continuously-moving carrier for the magazines or other articles to be addressed, and after the printing has been done and the carrier for the stencils is at rest the continuously-moving magazine will act to discharge the 75 stencil from the printing-point. It will be noticed that the carriers begin to diverge at this point; but the magazine will engage the stencil sufficiently to cause its discharge.

It will be further noticed that the printing 80 mechanism is dependent for its operation upon the step-by-step movement of the carrier.

In order to cause the magazine to be pressed onto the stencil with some force in order to 85 discharge it, I cause the bands 4 to move in a plane slightly below or rather within the plane of the periphery of the carrier. This is accomplished by arranging the rollers 28 28^x in the relation as shown in Fig. 1, by which 90 it will be noticed that the bands after leaving the printing-point will still cause the magazine to press on the stencil, and thus effect its discharge from the machine, whence it falls down an incline 28^a to a receptacle 28^b. The 95 rollers 28^x, one for each pair of bands 4, are suitably supported to one side of the rotary carrier, and such supports are indicated in dotted lines at 51 in Fig. 3. All the various shafts may be supported in a similar manner 100 by frame or standards.

Referring to Fig. 7, I show the complete machine in diagram in order to illustrate the manner in which the operation of the feeder and the mechanism which sends forward the 105 magazine are controlled by the absence of stencils. In this drawing, 52 indicates generally the feeding-rolls for magazines and wrapping-paper, such as are shown at 8 9 in my Letters Patent of the United States 110 granted May 17, 1903, No. 722,789, and 19^x, 20^x, 24^x, and 28^x are the folding-rollers which take the magazine and its wrapper and fold and wrap the same. 53 indicates generally pasting mechanism, which gives the 115 final fold to the wrapper and pastes the same down firmly. This pasting mechanism is the same as that disclosed in my application for Letters Patent of the United States, Serial No. 115,989, filed July 17, 1902, the paste- 120 roll being indicated at 54. The magazine on leaving the rolls 20^x 28^x is carried by the endless bands 55 to the rolls 56 57, whence the magazine passes through the rolls 57 and 58, from which it is taken by the bands 4 4 125 and carried thereby to the step-by-step feeder.

The complete machine is so organized that the feeding in of the magazines by the rolls 52, the folding by the rolls 19^x, 20^x, 24^x, and 28^x, and the operation of the pasting mechan- 130

ism is dependent upon the operation of a clutch which is located at the point indicated in the diagram by the word "clutch," such clutch being of any suitable construction and arrangement adapted to be operated electrically. To this clutch the circuit connections 49 and 50 extend, so that when contact is made by the hopper of the stencil becoming exhausted the electrical clutch will be operated and the machinery for feeding in, folding, and pasting will be stopped, and no magazines will be fed to the step-by-step feeder.

The fingers 11 are preferably cast on the carrier.

15 I claim as my invention—

1. In combination, a rotary carrier for printing-plates, carrier means for the magazines, to bring them automatically to the rotary printing-plate carrier, controlling means for the rotary carrier operated by the magazine or other article to be addressed to start said carrier from a position of rest, an impression plate or roller, and inking means associated with the said rotary carrier, substantially as described.

2. In combination, a rotary carrier for printing-plates, having means to hold the plates on its periphery, carrier means for the magazines disposed in the plane in which the rotary carrier moves to carry the magazines to the periphery of the carrier automatically, controlling means for the rotary carrier operated by the magazine or other article to be addressed to start said carrier from a position of rest, and inking and impression means associated with the said rotary carrier, substantially as described.

3. In combination in an addressing-machine, a rotary carrier for the printing-plates, driving mechanism for operating the carrier, a carrier for the magazines, controlling means for the rotary carrier operated by the movement of the magazine or other article to be addressed to start said carrier from a position of rest, and inking and impression means having their surfaces disposed at the periphery of the said rotary carrier and rendered effective by the movement thereof, substantially as described.

5. In combination in an addressing-machine, a rotary carrier for the printing-plates and printing means including inking means, said rotary carrier and inking means being controlled by the presence of a magazine to be started from a position of rest, substantially as described.

6. In combination in an addressing-machine, a rotary carrier for the printing-plates, driving means for the said carrier, and inking means, said driving means and inking means being controlled by the presence of a magazine to be addressed to be started from a position of rest, substantially as described.

65 7. In combination in an addressing-machine, a rotary carrier for the printing-plates,

means for feeding magazines to the periphery of said carrier, means for feeding printing-plates or stencils to the periphery of the carrier, means for controlling the movement of the carrier by the magazine to start said carrier from a position of rest and inking and impression means operating adjacent the periphery of the rotary carrier, substantially as described.

7. In combination, a rotary carrier for stencils, a carrier for the magazine, controlling means for the rotary carrier operated by the magazine or other article to be addressed to start said rotary carrier from a position of rest, an impression platen or roller, and inking means associated with the said rotary carrier and magazine-carrier, substantially as described.

8. In combination, a carrier, means for moving the same step by step and controlling means for the driving means operated by the magazine or other article, the said carrier moving under and being adapted to take stencils from a suitable supply and move them to the printing-point, substantially as described.

9. In combination in an addressing-machine, a rotary carrier for the stencils, driving mechanism for operating the carrier step by step, a carrier for the magazine and controlling means operated by the movement of the magazine or other article to be addressed, said carriers being arranged to place the magazine and stencil one on top of the other and inking means to which the carriers move the magazine and stencil, substantially as described.

10. In combination in an addressing-machine, a step-by-step carrier for the stencils, driving means therefor, and printing mechanism including inking means, said driving means and printing mechanism being controlled by the presence of a magazine to be addressed substantially as described.

11. In combination in an addressing-machine, a rotary carrier, driving mechanism for operating the same step by step controlling means extending to a point at or near the periphery of the carrier a second carrier moving at or near the periphery of the first carrier and into the plane of which the controlling means extend, and adapted to superimpose the magazine upon the stencil and printing mechanism including inking means to which the carriers move the superimposed parts, substantially as described.

12. In combination in an addressing-machine, a step-by-step carrier for the stencils, driving mechanism therefor, controlling means for the driving mechanism arranged to be operated by the presence of the magazine or other article to be addressed and printing means driven from the step-by-step carrier substantially as described.

13. In combination, a rotary carrier for

the stencils, driving mechanism therefor, controlling means for the driving mechanism, a carrier moving at the periphery of the carrier first mentioned, for the magazines or like articles, and intermittently-rotating impression and inking rolls on opposite sides of the magazine-carrier, substantially as described.

14. In combination, a rotary carrier in the form of a frame having an overhanging portion and an open periphery, teeth on the said carrier for engaging stencils, a carrier for the magazines or the like moving substantially at the periphery of the stencil-carrier, an inking roller or pad beneath the overhanging portion of the rotary frame, and an impression-roller between which and the periphery of the carrier the magazine and stencil are passed substantially as described.

15. In combination, a step-by-step carrier for the stencils, a continuously-moving carrier for the magazines or other articles to be addressed, controlling means for the stencil-carrier operated by the passage of a magazine, printing means comprising members located on opposite sides of the path of the magazine and stencil and driving means therefor, the said magazine being adapted to discharge the stencil after the stencil-carrier comes to rest, substantially as described.

16. In combination, a rotary carrier for the stencils, driving means for moving the same step by step, traveling bands for the magazine and controlling means operated by the magazine for controlling the driving mechanism of the stencil-carrier, said traveling bands being guided to conform substantially to the periphery of the carrier to maintain control of the assembled magazine and stencil, substantially as described.

17. In combination, a step-by-step rotary carrier for the stencils, a driving mechanism therefor, controlling means for the driving mechanism whereby the carrier is operated step by step, a carrier for the magazines, inking and impression rollers and gearing for driving the same operated from the step-by-step carrier, substantially as described.

18. In combination, a rotary carrier, a constantly-rotating ratchet-wheel, pawls on the carrier to engage the ratchet-wheel, a switch-lever for holding the pawls out of engagement, a latch controlling the switch-lever and a magazine-carrier arranged to move the magazine so as to operate the latch, said latch extending substantially radially of the carrier, substantially as described.

19. In combination, a carrier, a con-

stantly-rotating ratchet-wheel, a pawl on the carrier to engage the same, a switch-lever controlling the position of the pawl, a latch for controlling the switch-lever and means for raising the switch-lever to engage the latch, said means being on the carrier and engaging a portion of the switch-lever, substantially as described.

20. In combination, a carrier, a constantly-rotating ratchet-wheel, a pawl on the carrier, a switch-lever for controlling the pawl, a latch controlling the switch-lever, and a pin on the carrier to engage a part of the switch-lever to return the same to normal position, substantially as described.

21. In an addressing-machine, a rotary carrier for the stencils or printing-plates, means for automatically supplying stencils to the periphery of the rotary carrier, impression means, means for automatically feeding the magazines, driving means, and means for controlling the same by the magazine to start the rotary carrier from a position of rest, said carrier rotating continuously as long as the magazines are being properly fed to meet the stencils or printing-plates in proper order and becoming step by step under irregularity of feed, substantially as described.

22. In combination, a hopper for the stencils, a carrier for the stencils having teeth and rubber-covered contacting portions to engage the stencils means for feeding magazines to the stencils, and inking and impression means substantially as described.

23. In combination, in an addressing-machine, a rotary step-by-step carrier for the stencils, a hopper, the said carrier being adapted to take the stencils from the hopper and move them to a point beyond the hopper where the carrier comes to rest, means for superimposing a magazine or other article upon the stencil substantially at this point, said means including a carrier for the magazine, controlling means for the step-by-step carrier acted upon by the magazine to start the step-by-step carrier and printing means to which the step-by-step carrier and the magazine-carrier move the magazine and stencil in superimposed position, substantially as described.

In testimony whereof I affix my signature in presence of two witnesses.

CHARLES OWENS.
